Primary Examiner — Carla Jobe Wright*(74) Attorney, Agent, or Firm* — Christopher & Weisberg, P.A.(57) **CLAIM**

The ornamental design for a translucent mobile device case, as shown and described.

DESCRIPTION

FIG. 1 is front perspective view of a translucent mobile device case;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash broken lines represent boundaries of the claimed design. The dash-dash broken lines depict unclaimed environment. The broken lines form no part of the claimed design.
